(57) **CLAIM**

The ornamental design for a bayonet plunger release member, as shown and described.

DESCRIPTION

FIG. 1 is a top perspective view of a bayonet plunger release member;

FIG. 2 is a bottom perspective view of the bayonet plunger release member;

FIG. 3 is a front view of the bayonet plunger release member;

FIG. 4 is a rear view of the bayonet plunger release member;

FIG. 5 is a right side view of the bayonet plunger release member;

FIG. 6 is a left side of the bayonet plunger release member;

FIG. 7 is a top view of the bayonet plunger release member;

and,

FIG. 8 is a bottom view of the bayonet plunger release member.

The broken lines shown in the drawings illustrate the environment of the claimed design and form no part thereof.
